UNITED STATES PATENT OFFICE.

CHARLES HAZOR SMITH, OF CHICAGO, ILLINOIS, ASSIGNOR TO THE MANTLE LAMP COMPANY OF AMERICA, OF CHICAGO, ILLINOIS, A CORPORATION OF ILLINOIS.

MANTLE-CAP AND BURNER-CONE.

1,255,653.

Specification of Letters Patent.

Patented Feb. 5, 1918.

Application filed October 15, 1915. Serial No. 55,983.

To all whom it may concern:

Be it known that I, CHARLES HAZOR SMITH, a citizen of the United States, residing at Chicago, in the county of Cook and State of Illinois, have invented certain new and useful Improvements in Mantle-Caps and Burner-Cones; and I do hereby declare the following to be a full, clear, and exact description of the invention, such as will enable others skilled in the art to which it appertains to make and use the same.

In the manufacture and operation of incandescent vapor gas lamps employing a burner cone of the type illustrated in my prior Patent No. 988902, dated April 4, 1911, considerable difficulty has been experienced in manufacturing a cone of the type therein disclosed to retain the same in position on a burner. It has been found that it is necessary to hold the depth of the burner cone to a predetermined, definite measurement, to coöperate with the burner spreader, the wicktubes and the wick. One of the critical dimensions in a burner, and one which affects the operation of a burner of this classification, resides in the distance between the inside of the top horizontal flange of the cone, which may be herein referred to as a cone cap, and the top of the outside wick-tube flange of a burner with which the cone is designed to be used. The cone should be mounted on the burner with certain predetermined relation to the upper ends of the wicktubes and the structure carried thereby.

In the manufacture of these cones, it has been found difficult to maintain the accuracy of the construction of the cone when made by the old method, in that the body of the cone is liable to be distorted out of its true circular formation.

This invention contemplates the provision of improved means for retaining a mantle cap to the gallery of a burner, as well as improved features in the construction of the cap, such features residing in the provision of means to prevent the lower section of the cap from getting out of round, that is to say, being distorted from its true circular formation.

In carrying out the invention, a practical form is disclosed in the accompanying drawings, wherein novel attaching means are provided for the cap to be associated with means carried by the burner gallery. The burner cone is illustrated as having a substantially

conical form, as disclosed in my prior patent, but in addition thereto, there is provided an annular flange having a notch which is designed to permit an ear, carried by the burner gallery to pass through the notch and engage the flange. The notch does not extend to the full depth of the flange, thereby retaining the strength of the flange at the base of the cap, to prevent distortion of the cap. It is preferred also to provide frictional locking means on the flange which may be effected by upturning the edge of the flange adjacent the cut out portion, and if desired, by upsetting the edge of the flange opposite to the upturned edge to make a non-entrant stop to engage the gallery retaining mechanism, thereby making it impossible to attach the cap in an incorrect manner to the gallery.

In the accompanying drawings—

Figure 1 is a side elevation, disclosing a burner cone with a mantle and a mantle support maintained in position thereon.

Fig. 2 is a vertical, sectional view through the burner cone and mantle support.

Fig. 3 is a plan view of the burner cone and mantle support.

Fig. 4 is a bottom plan view of the burner cone.

Fig. 5 is a detail view, in side elevation, of locking means carried by the burner to engage the slots of the burner cone.

Fig. 6 is a detail plan view of the means to lock the burner cone disclosed in Fig. 5.

Referring to the embodiment of the device illustrated in the accompanying drawings, the burner cone is illustrated at 1, and is shown contracted at the upper portion as at 2. The upper portion 2, terminates in an inturned, annular flange, indicated at 3, and providing a central opening 4. The wall of the member 1 is shown as substantially vertical, and at its lower edge is provided with a protruding or external annular flange 5. This flange may be of any desired width, and is preferably positioned to form the base of the burner cone. The structure described may be termed a cone-cap, by virtue of its use as a cap or mantle support and a cone for the gallery of a burner. The burner cone is designed particularly for use on incandescent mantle lamps of the blue flame wick type, and coöperates with other parts of the burner to direct air over the wick and to facilitate the proper combustion

of the fuel. For this reason, the flange 3 and the flange 5 of the cone-cap are essential parts of a structure for the purposes described, and it is desired to maintain their 5 relative positions in the completed article. Moreover, the proper circular formation of the parts 1 and 2 should be maintained to secure uniform and proper air passage between the inside of the cone and the wick 10 tube flange. It should be noted, however, that the accompanying drawings are not made to a scale, but are merely presented as 15 illustrative of a practical form of the device.

The side of the member 1 of the burner 20 cone may be perforated as at 6 to receive tongues 7 of a supporting element 8, which is adapted to be secured by means of the tongues 7 to the burner cone. This supporting element is shown provided with a tubular member 9 into which may be inserted a 25 wire support 10 for the mantle.

The mantle support is preferably of a continuous piece of metal, such as wire, bent to form the side members, the ends of which 25 are adapted to be secured permanently in the tubular members by compressing the metal of said tubular member, as at 11, to securely bind the wire 10. Intermediate the ends of the wire 10, the side members may be 30 bent as at 12, toward each other, to an upper extremity 13. The part positioned between 12 and 13 is curved to form a seat as at 14, upon which may rest a suitable protective element, not shown, in the packing and shipping of the mantle. Between the elevated 35 curved portions 13, the wire is bent downwardly to form a widened notch 15, which serves as means to suspend a mantle 16 by means of its suspension loop 17. The 40 inclination of the wire from the points 13 to the center of the notch 15 is preferably central of the burner cone, so that the mantle will hang substantially central of its wire supporting element. By this arrangement, 45 the lower portion 18 of the mantle will inclose the conical upper part 2 of the burner cone-cap.

In the practical operation of a lamp, it is desired that the combined mantle cap and 50 burner cone shall be securely mounted upon the burner. One means of locking the burner cone upon the lamp is shown in the accompanying drawings, wherein the flange 5 is provided with a notch 20, which does not 55 extend the full depth of the flange, but leaves a part of the flange, indicated at 21, interposed between the notch 20 and the side wall of the mantle cap 1. This remaining portion of the metal of the flange 5, serves to 60 strengthen the cap circumferentially at the base to prevent injury to the cap in distorting it out of its proper circular formation. In Figs. 3 and 4, a plurality of these notches 20 are illustrated, such notches being positioned opposite to each other. These notches 65

are designed to coöperate with a locking ear 22 carried by a part of the burner, such as the horizontal flange of the carrier. The ear 22 is shown stamped up from the metal of the burner, and may be elevated more at one 70 end, as at 23, than at the other end, as at 24, from the structure from which it is stamped up, to thereby provide an inclined locking ear.

In applying the burner cone-cap to a mantle, the cap is positioned upon the burner parts in such manner that the slot 20 registers with a locking ear 22, whereupon the cap may thereafter be pressed upon the burner so that its annular flange 5 bears 80 upon the burner parts to which it is to be applied, and rotated to bring the ear 22 into engagement with the unnotched part of the flange 5. To rotate the flange in one direction, and thereby insure the proper adjustment of a cap upon the burner, the edge of the flange 5 adjacent the slot 20 may be slightly turned up as at 25 to form a non-entrant obstruction. To securely bind the burner cone to the burner structure, the edge 90 of the flange opposite to the non-entrant edge 25 may be slightly turned up along the edge of the flange 5 as at 26, such upsetting or turning up of the edge 26 being gradual from the slot 20, but it is preferred that this 95 upsetting of the edge 26 shall not extend the full depth of the flange. By this arrangement, the inclination of the edge 22, coöperating with the inclined edge 26, as shown in Fig. 1, will provide the gradual engagement between the ear 22 and the flange 5 to 100 securely maintain the burner cone in position on the burner.

It is obvious that various alterations and modifications may be made in the form and 105 operation of the parts to meet the exigencies of the service of the cone-cap. The right is reserved, therefore, to make such changes and alterations as fairly fall within the scope of the appended claims. 110

Having thus described my invention, what I claim as new and desire to secure by Letters Patent, is:

1. As an article of manufacture, a combined mantle cap and burner cone comprising a base having an annular flange provided with opposed notches which extend into the flange for a part of the depth thereof, the edge of the flange adjacent the notches being distorted to provide means to 115 engage by a locking device.

2. As an article of manufacture, a burner cone-cap having a contracted upper portion terminating in an inturned annular flange, and a lower, annular flange forming the supporting base for said cone-cap provided with a notch, the flange being upset at its outer edge to secure the cap in its adjusted 125 position on a burner.

3. As an article of manufacture, a com- 130

5 bined mantle cap and burner cone, comprising a body having an annular, inturned, upper flange and a protruding, annular lower flange spaced at a predetermined position
5 with relation to said upper flange, a looped wire mantle support having its extremities secured to said cap, a mantle secured on said support to be maintained in position by the mantle cap carried by the body of the cap,
10 said lower flange being provided with a notch, and retaining means comprising the upsetting of the outer edge of the flange adjacent said notch.
4. In an incandescent vapor gas lamp of
15 the blue flame wick type, a burner having a gallery provided with an upstanding horizontal ear arranged diagonally with relation to the plane of the gallery surface from which the ear is formed, and a burner cone
20 adapted to be removably mounted on the gallery, said cone having a substantially horizontal flange provided with a notch which extends into said flange to permit the
25 upstanding ear of the gallery to pass therethrough, said flange being provided also

with an inclined upturned edge to coöperate with the inclination of the ear of the gallery, to serve as a locking means to retain the cap tightly into engagement with the gallery.

5. The combination with a burner having 30 a gallery provided with an upstanding ear formed thereon, and a burner cone adapted to be mounted on said gallery, said burner cone including an annular base flange provided with a notch which extends for a part 35 of the depth of the flange to permit the upstanding ear of the gallery to pass therethrough and retain the strength of the flange, the outer edge of the flange being distorted along one side of the notch to be 40 engaged by the ear when the cone is rotated on the gallery, and distorted on the other side of the notch to form a non-entrant stop.

In testimony whereof, I affix my signature, in presence of two witnesses.

CHARLES HAZOR SMITH.
